UNITED STATES PATENT OFFICE.

EDWARD F. ABBEY, OF TOLEDO, OHIO.

BRUSH-MACHINE.

SPECIFICATION forming part of Letters Patent No. 724,371, dated March 31, 1903.

Application filed May 24, 1902. Serial No. 108,857. (No model.)

To all whom it may concern:

Be it known that I, EDWARD F. ABBEY, of Toledo, in the county of Lucas, State of Ohio, have invented certain new and useful Improvements in Brush-Machines; and I do hereby declare the following to be a full, clear, and exact description of the same, reference being had to the accompanying drawings, forming a part of this specification, and to the letters of reference marked thereon.

This invention relates to improvements in machinery used in the formation of brushes, and especially in machinery used in the formation of brushes having what are known as "solid" backs—that is to say, in which holes are drilled in a brush-block at the proper distances apart and at the proper angles for the reception of the bristles, and the bristles are subsequently inserted in said holes and held by means of metallic retainers—although, as will presently appear, the invention made the subject-matter of this application is capable of a much wider range of usefulness and may be employed to advantage in connection with any desired type of machine wherein the brush-block may be positioned automatically, either for the insertion of the bristles or for the formation of the holes for the reception of the bristles.

The invention consists, therefore, primarily in an improved mechanism for automatically positioning the brush-block.

The invention further consists in certain novel details of construction and combinations and arrangements of parts, all as will hereinafter be described, and pointed out particularly in the appended claims.

Referring to the accompanying drawings, Figure 1 is a side elevation of a machine embodying my present improvements, portions of the frame and mechanism being shown in section and broken away to disclose underlying parts. Fig. 2 is a top plan view of a brush-block carrier. Fig. 3 is a front elevation of the same, showing the upper end of the adjusting-shaft. Fig. 4 is a detail sectional view showing a portion of the mechanism for turning the adjacent shaft on its longitudinal axis. Fig. 5 is a perspective view showing details of the mechanism for controlling the horizontal adjustment of the block-carrier.

Like letters of reference in the several figures indicate the same parts.

In illustrating my present invention I have shown it in connection with a machine for inserting bristles or tufts into the brush-block, the type of machine illustrated being one now in extensive public use and known as the "Gane" filling-machine. This type of machine is well illustrated in United States Letters Patent No. 378,130, granted to J. V. Gane February 21, 1888; but it will be understood that the invention may be used in connection with any other desired type of machine, either for inserting the bristles or having a drill or drills for forming the holes into which the bristles are inserted.

In the Gane machine illustrated the letters A and A' indicate the main frame of the machine, in which all of the working parts are mounted; B, the inserter; C, the inserter-operating lever; D, the adjustable bristle-support; E, the reciprocatory base for the block-carrier, and F F' the mechanism for reciprocating said base from the main shafts G and G'.

In this machine the block has heretofore been positioned by hand, so as to present its face in proper position and at the proper angle for the insertion of the bristles; but in accordance with my present invention I now propose to position the block automatically by an improved mechanism, thereby relieving the operator of this labor and insuring a presentation of the block at a mathematically-correct angle and in correct position to insure the bristles in the completed brush being held in proper relation to each other and to the block-back. To accomplish this desirable end, the block or brush-back is held in a carrier mounted on suitable centers having axes at substantially right angles to each other and capable of an adjustment to vary the radius or arc described by the block or back, with a controlling mechanism operating through a single connection and embodying pattern disks or cams, which will so move the controlling mechanism as to properly position the block. In said drawings the block-carrier is indicated by the letter H and preferably consists of a rectangular frame having suitable clamps h mounted to slide therein and adjustable toward and from each other.

by means of a screw-shaft H^5 , having right and left threads thereon and controlled by a hand-wheel, all as indicated at H' in Fig. 3. The screw H^5 is held against longitudinal movement by a center H^6 , and the latter is adjustably mounted in the frame H by means of a set-screw or clamp H^7 , whereby the center may be shifted for irregular blocks or the block may be set to secure a greater degree 10 of slant for the bristles at one end than at the other. This block-carrier is provided with rearwardly-extending arms or rods I , adjustably mounted in trunnions i , taking pivotal bearings in a transverse head or frame K , 15 the arrangement being such that the carrier, with its block, is free to swing vertically with its block on the trunnions i . The head or frame K is provided with a central rearwardly-extending stem k , adjustably mounted 20 in a trunnion L , which latter pivots in a bearing L' , formed or mounted on the forward end of the reciprocatory base or slide E , before referred to. The axis of the trunnion L is at right angles to the axis of the trunnion i , and by adjusting the stems or rods I or k in their trunnions it is obvious that the curvature of the arc or arcs described by the face of the carrier or block mounted therein may be varied at will, and inasmuch as in 25 practically all brushes the curvature of the arc on the longer diameter of the face of the brush is less than the curvature on the shorter diameter the trunnion L is located some distance in the rear of the trunnions i , and in 30 the particular embodiment illustrated in the drawings the longest diameter of the brush, block will be substantially horizontal, although it is obvious that this is an arbitrary arrangement and is not a necessary incident 35 to the present invention.

The control or adjustment of the carrier H is secured through the medium of a vertically - movable and horizontally - rotatable shaft M , having at its upper end a crank M' , 40 provided with a track or way m , pivotally mounted thereon and extending horizontally or in the line of reciprocatory movement of the carrier H . This track or way m is adapted to coöperate with or receive a block 45 N , mounted on the carrier H , so as to be capable of sliding on the track or way, the connection between the track or way being preferably formed by dovetailing one into the other, so as to hold the carrier and shaft M 50 against independent vertical movement, as will be understood from an inspection of Fig. 3 of the drawings. The block N is adjustably connected with the carrier H , the adjustable connection shown being a conventional one, 55 consisting of angle-irons N^5 , secured to the carrier by set-screws N^6 passing through slots N^7 in the angle-irons, so as to accommodate blocks of different thickness or to increase or diminish the distance between the 60 rows of holes on the face of the block, thereby permitting of the making of larger or 65 smaller brushes with the same pattern-disk,

and said block N is preferably pivoted between the angle-irons by a pivot O , so as to permit the carrier H to swing vertically on 70 the trunnions i ; but said block takes a bearing on the track m of sufficient length to hold said track in the line of reciprocation back and forth of the carrier as said carrier advances to or recedes from the position where 75 the brush-block coöperates with the inserter or drill, as the case may be.

Obviously now if the shaft M be moved vertically the carrier H will be swung on the trunnions i , and if said shaft be rotated it 80 will, through the crank M' and track, as aforesaid, swing the carrier H horizontally on the trunnion L , and in any of its positions of adjustment the said carrier H is free to reciprocate horizontally. Thus it is only necessary 85 to provide a means whereby the shaft M may be given the desired movements to accurately position the brush-block for the operation of the coöperating member. To secure these movements of the shaft M and carrier H , I 90 provide a pair of pattern disks or cams $P P'$, Fig. 1, journaled on a center p and adapted to be rotated intermittently by means of a worm p' , a pawl and ratchet p^2 , and a driving-cam p^3 , mounted on the main shaft G' and 95 operating through a connection p^4 (the end of which surrounds the cam, so as to provide contacting-surfaces therefor) to operate the worm and pattern-disks at the proper time, or when the carrier H and inserter B or 100 equivalent coöperating members are retracted from the operative position. Resting on the pattern-disk P' is the forward end of an arm R , pivotally supported on a shaft R' and adapted at its forward end to directly support the shaft M . Thus as the disk P' is rotated the shaft M will be raised or lowered, in accordance with the contour outlines of the disk P' . A second arm S , corresponding to the arm R , rests on the pattern-disk P , this arm S 110 being also pivotally supported on the shaft R' and at its forward end is connected by a link s with a bell-crank lever S' , pivoted on a portion of the main frame. The opposite arm of the bell-crank lever S' is pivotally connected by a link T with a lever T' , the axis of which is formed by the shaft M , but the support for which is formed by a bracket S^2 115 on the main frame. The outer end of this lever T' embraces a rod U , which is connected 120 with the shaft M , so as to form a crank, which when the lever T' is oscillated or moved on its axis will rotate the shaft M to a corresponding degree. The connection between the lever T' and crank U is preferably formed 125 by a ball-bearing U' , which will permit the crank or rod U and shaft M , which is journaled in the bracket S^2 on the main frame, to move vertically without obstruction, but will hold said shaft M' accurately in its angular 130 position of adjustment, dependent upon the position of the lever T' as controlled by the pattern-disk P . In mechanism of this character it is desirable that the arms or parts

Controlling the position of the carrier H should be lifted out of contact with the pattern disk or disks during the feeding movement or rotation of the disks, and this is especially desirable where sharp changes in the contour outlines of the disks occur and where, as in the present instance, it is found desirable to form a seat in the edge of each of the disks for the arm or coöperating member to rest in in each position of adjustment. To accomplish this, the arms R and S are at their inner ends rigidly connected with ratchet-wheels V V', journaled on the shaft R', and the shaft R' has journaled on it a pair of pawl-carrying arms V², connected by links V³ with operating-levers V⁴, pivoted on the frame A and adapted to be moved by a cam or cams V⁵ on the main shaft G'. The pawl-carriers V² carry pawls W, adapted to engage the ratchet-wheels V V' whenever the carriers V² are moved rearwardly by the cam V⁵ and when so moved to lift the arms R and S out of contact with the pattern-disks. The cam V⁵ operates just in advance of the cam p³, which rotates the pattern-disks. Cam V⁵ is so constructed that it allows the pawls W to move forwardly far enough to insure the lowering of arms R and S on the pattern-disks P P', so as to position the carrier H accurately at each operation. The controlling-springs X are adjustable on the rods V³ in position to engage the rear ends of the pawls W and hold them from again engaging the ratchets V V' on the rearward motion until they have passed the desired number of teeth to overcome the irregularities of the pattern-disks P P'.

To secure a wide range of adjustment, the link V³ may be adjustably connected with the lever V', as shown in Fig. 1, and, furthermore, the link T, Fig. 4, is also preferably adjustably secured to the lever T', as illustrated clearly in Fig. 4, by a set-screw T⁵, whereby the distance between the holes in a row may be varied for large or small brushes while using the same pattern-disk.

With the mechanism thus described it will be seen that absolutely accurate and uniform results may be secured in the completed brushes and what is of greater importance the entire operation so far as the positioning of the brush-block is concerned is automatically accomplished. As in said Gane machine, in order to start the mechanism the operator places his foot on the treadle Z and depresses the same; but inasmuch as in the present embodiment it is desirable that the machine should be automatically stopped when the pattern-disks have made a complete revolution a stop mechanism is preferably introduced, which will be controlled by the pattern-disks on their shaft. Obviously any well-known or preferred stop mechanism may be employed, and I have shown a conventional mechanism consisting of a catch Z', held forward by a spring in position to catch and hold the treadle depressed when once pushed down

by the operator, and this catch is adapted to be automatically released, so as to allow the treadle to rise and stop the mechanism, by means of a projection Z² (shown in Fig. 1) on the shaft p. The projection Z² pushes downwardly on a rod Z³ and through a bell-crank Z⁴ and rod Z⁵ releases the catch Z' when the pattern-disks have made a complete revolution.

Having thus described my invention, what I claim as new, and desire to secure by Letters Patent, is—

1. In a brush-machine, the combination with a brush-block carrier mounted to swing on trunnions with their axes at right angles to each other, of a positioning mechanism for said carrier, embodying a crank-shaft mounted to move longitudinally and to rotate on its longitudinal axis, pattern-disks mechanism intermediate the disks and shaft for controlling the movement of said shaft, a track or way mounted on the crank of said shaft and a block resting on said track or way and connected with the carrier; substantially as described.

2. In a brush-machine, the combination with a brush-block carrier mounted to swing vertically or horizontally on independent trunnions, of a positioning member for said carrier embodying a longitudinally-movable and rotary crank-shaft, pattern-disks and intermediate controlling mechanism for positioning said shaft in both its longitudinal and rotary positions of adjustment, a track or way pivotally mounted on the upper crank end of said shaft and a block pivotally mounted on the carrier and resting on the track or way; substantially as described.

3. In a brush-machine, the combination with a block-carrier mounted to swing vertically and horizontally on independent trunnions and a positioning mechanism embodying a longitudinally-movable and rotary crank-shaft, of pattern-disks one in connection with intermediate mechanism for positioning said shaft longitudinally and the other for positioning said shaft in its rotary movement and connections between said shaft and the last-mentioned pattern-disk and embodying connecting-links and a lever through which the shaft may move longitudinally but which has an axis coincident with the axis of the shaft and moves on its axis coincident with the angular movement of the shaft; substantially as described.

4. In a brush-machine the combination with the block-carrier movable vertically or horizontally, a crank-shaft movable longitudinally and capable of a rotary movement, with pattern-disks for positioning said shaft, of trains of connections between said shaft and disks the connections for determining the rotary position of the shaft embodying a rod connected with said shaft, a lever having an axis coincident with said shaft and embracing the rod whereby the shaft may be moved longitudinally independently of the lever and

connections intermediate the lever and disk; substantially as described.

5. In a brush-machine the combination of a brush-block carrier, pattern-disks, carrier-controlling mechanisms adapted to contact with said disks to position said carrier, feeding mechanism for the disks, and an intermittently-operating elevating mechanism for the carrier-controlling mechanism, whereby 10 during the feed of the disks said controlling mechanism may be held out of engagement therewith; substantially as described.

6. In a brush-machine the combination with a brush-block carrier, pattern-disks, a rotary and longitudinally-movable shaft for positioning the carrier, means for giving the shaft a rotary and longitudinal movement and an independent elevating mechanism for said shaft, and driving mechanism for operating said elevating mechanism during the feed movement of the disks; substantially as described.

7. In a brush-machine the combination with a brush-block carrier movable vertically and horizontally, and controlling mechanism 25 for said carrier embodying pattern-disks and an intermediate mechanism positioned by said pattern-disks, of an elevating mechanism for the carrier independent of the pattern-disks and embodying an elevating-arm, a reciprocating pawl, a ratchet connected with the arm, a driving mechanism and a trip for disengaging the pawl when the carrier is lowered to permit the pattern-disks to become 30 effective in positioning the carrier; substantially as described.

8. In a brush-machine the combination with a bristle-inserter, a driving mechanism therefor and a reciprocating support for the brush-block, of a brush-block carrier pivotally connected with said support to swing vertically and horizontally on independent centers, a positioning mechanism connected directly with said brush-block carrier and independent of the support, pattern-disks for determining the adjustment of said positioning mechanism and driving mechanism for said pattern-disks operating intermittently to position the carrier while the inserter and support are in their inoperative positions; substantially as described.

9. In a brush-machine, the combination with a bristle-inserter, a driving mechanism therefor and a reciprocating support for the brush-block, of a brush-block carrier pivot-

ally connected with said support to swing vertically and horizontally on independent centers, a positioning mechanism connected directly with said brush-block carrier and independent of the support, pattern-disks and 60 intermediate connections for determining the adjustment of said positioning mechanism, driving mechanism for said pattern-disks operating intermittently to position the carrier while the inserter and support are in their 65 inoperative positions and a stop mechanism controlled by the driving mechanism for the pattern-disk for arresting the movement of the driving mechanism; substantially as described.

10. In a brush-machine, the combination with a reciprocating bristle-inserter and a reciprocating brush-carrier mounted on independent trunnions to move vertically and horizontally and a positioning mechanism for 75 said brush-carrier embodying a rotary and longitudinally-movable crank-shaft, a track or way controlled by said shaft, a guide on the carrier traveling on said track or way and pattern-disks and connections intermediate 80 said disks and crank-shaft for positioning the crank-shaft and carrier; substantially as described.

11. In a brush-machine, a brush-block carrier consisting of a frame, clamps movable 85 toward and from each other in the frame, a screw for moving the clamps and a center between the clamps for holding the screw against longitudinal movement; adjustably mounted in the frame, substantially as de- 90 scribed.

12. In a brush-machine, a brush-block carrier movable on centers vertically and horizontally, and a positioning mechanism therefor having a track or way, of a guide-block 95 on the carrier for coöperation with the track or way and adjustably connected with the carrier; substantially as described.

13. In a brush-machine, a brush-block carrier movable on centers vertically and horizontally and a positioning mechanism therefor having a track or way, of a guide-block 100 on the carrier for coöperation with the track or way said guide-block being pivotally and adjustably connected with the carrier; sub- 105 stantially as described.
